UNITED STATES PATENT OFFICE.

HIRAM E. MOON, OF RICHMOND, INDIANA.

MAP AND CHART CASE.

SPECIFICATION forming part of Letters Patent No. 276,267, dated April 24, 1883.

Application filed December 22, 1882. (Model.)

To all whom it may concern:

Be it known that I, HIRAM E. MOON, a citizen of the United States, residing at Richmond, in the county of Wayne and State of Indiana, 5 have invented a new and useful Map and Chart Case, of which the following is a specification.

The object of my invention is to provide cheap and convenient means of preserving maps, charts, and other printed matter, to facilitate their use in schools, colleges, and libraries, and to economize space by putting what is wanted where it is wanted. It is especially adapted to the display of maps, charts, and alphabetical sheets for primary schools. It is also well adapted to high schools and colleges, and for graded schools it has the further advantage of accommodating all grades by containing matter adapted to each grade, which can be readily removed and as readily replaced in the case 20 when not in use. I attain these objects by the mechanism illustrated in the accompanying drawings, in which—

Figure 1 is a perspective view of the case closed as it hangs against the wall of the school-room or library. Fig. 2 is a detailed view, in perspective, of the case open, showing a swinging leaf or bracket turning on a simple hinge, having display-sheets suspended from its upper edge, as well as having maps or charts pasted 25 on one or both sides of the leaf itself. Fig. 3 represents the swinging leaf turned back, showing the other side of the swinging leaf, and also of the display-sheets.

Similar letters refer to similar parts throughout the several views.

The front recessed frame, B, and the rear recessed frame, L, with panels A and E, may be made any desired size or pattern, the hangers C C, the swinging leaf or bracket G, hinged to 30 the front or rear frame, may be made detachable, if desired. The display sheets or maps H are attached to the upper edge of the leaf by means of a strip or roller, I, pivoted or otherwise. The hangers C C are fastened to the 35 back frame, L, for the purpose of support when the case is in position. The front and rear frames may both swing on brackets attached to the wall, so the whole case may be turned from one side to the other, or may be opened 40 like a book on the hinge-line J J. The wire leaf-holders D D are attached to the front and rear frames, B L, and may, when the case is

open, be turned in over one or more swinging leaves to hold them in position.

To give a better understanding of my invention, I will describe the method of operating it. The maps, charts, or other matter to be studied or displayed may be attached by their upper edges to the strip or roller I, which is attached in any desired way to the upper edge 55 of the swinging leaf G, or may be pasted on the sides of the leaf. When display-sheets are attached to top of swinging leaf G by the strip I the case is opened and the leaf G is turned out at or near a right angle to the wall or support. The display-sheets can be thrown to the right or left side of the swinging leaf until the desired map or chart is reached. Then the leaf can be turned to left or right to accommodate the school or class, or the swinging leaf G may 60 be lifted off its hinges K K and taken to another room or place and hung up by the same hinges, and the display-sheets and the sheets pasted upon its surface can be exhibited in the same way as if hung in the case. In this way 65 any number of leaves G may be added to the case, one or more of them having display-sheets H mounted upon their upper edge and maps and charts pasted upon their surfaces. In this way it will be seen that one subject—say physiological charts—may be pasted upon the leaf-surfaces. A reading-chart may be mounted upon top of one leaf G, charts of penmanship, 70 arithmetic, civil government, drawing, &c. Another set, consisting of a series of charts, 75 may be mounted upon another leaf until a complete outfit can be neatly and permanently mounted in one case, giving the teacher all the facilities necessary to the best possible teaching. When not in use, all the contents of this 80 case can be locked up and kept secure against dust, light, or intruders.

This invention is supplementary to a patent granted me on map and chart cases January 11, A. D. 1881, and again November 8, 1881, and 85 also the Doubler patent granted June 8, 1880, and now controlled exclusively by me by assignment from the patentees.

What I claim as new and of my invention, and desire to secure by Letters Patent, is— 90

1. In a map and chart case, leaves or brackets G, having the roller or strip I thereon for holding maps or charts H, the leaves being adapted to swing on hinges and fold into the 95

case, substantially as shown and described, and for the purpose set forth.

2. The combination, in a map and chart case having leaves G, with rollers or strips I thereon for holding maps H, the leaves being adapted to swing on hinges and to fold into recesses in the frames L B, of the wire leaf-holders D D, attached to the sides of the case, substantially as shown, and for the purpose set forth.

10 3. In a map and chart case, leaves or brackets G, having the roller or strips I thereon for

holding maps or charts H, the leaves adapted to swing on hinges and capable of being readily detached from the case, and of having maps, charts, or other printed matter pasted upon 15 their surfaces, substantially as shown and described, and for the purpose set forth.

HIRAM E. MOON.
